CLAIM

The ornamental design for a flower pot cover, as shown and described.

DESCRIPTION

FIG. 1 is a top plan view of our new flower pot cover design;

FIG. 2 is a bottom plan view thereof;

FIG. 3 is a perspective view thereof;

FIG. 4 is a side elevational view thereof;

FIG. 5 is a side elevational view of the design of FIG. 1, the only difference being the angle of the skirt; and,

FIG. 6 is a side elevational view of the design of FIG. 1, the only difference being the angle of the skirt.

The flower pot cover has no substantial thickness.

UNITED STATES PATENT AND TRADEMARK OFFICE
CERTIFICATE OF CORRECTION

PATENT NO. : Des. 362,824
DATED : October 3, 1995
INVENTOR(S) : Weder et al.

It is certified that error appears in the above-identified patent and that said Letters Patent is hereby corrected as shown below:

Cover Sheet, under 'Related U.S. Application Data',
item, [63], line 1, after '1991,' please insert
--now U.S. Patent No. Des. 365,302--.

Cover Sheet, under 'Related U.S. Application Data',
item, [63], line 3, please delete "which is a
continuation-in-part of".

Cover Sheet, under 'Related U.S. Application Data',
item, [63], line 4, please delete "which is a
continuation-in-part of ", and substitute therefor
--now U.S. Patent No. Des. 358,113, and--.

Cover Sheet, under 'Related U.S. Application Data',
item, [63], lines 5-6, please delete "which is a
continuation-in-part of".

Signed and Sealed this
